METHOD OF FORMING VEHICLE WHEEL
RIMS AND THE LIKEFrank H. Le Jeune, Detroit, Mich., assignor to
Kelsey-Hayes Wheel Company, Detroit, Mich.,
a corporation of Delaware

Application October 28, 1935, Serial No. 47,181

2 Claims. (Cl. 29—159.1)

This invention relates generally to a method of forming an annulus to a predetermined cross sectional contour and refers more particularly to an improved method of forming vehicle wheel 5 rims of the drop-center type.

One of the principal objects of the present invention consists in the provision of a method of the character set forth embodying a fewer number of operations than methods employed in the 10 past to form vehicle wheel rims of the general contour previously set forth, rendering it possible to not only employ simpler apparatus for carrying out the method, but, at the same time offering the possibility of increasing the production 15 of vehicle wheel rims or similar articles and reducing the cost of the latter.

Another advantageous feature of the present invention consists in the provision of a method of the character set forth rendering it possible to 20 form a relatively small diameter annulus of heavy gage stock to a predetermined irregular cross sectional contour.

A further feature of the present invention which is largely responsible for imparting the 25 foregoing advantages to my improved method consists in curling the opposite sides of the annular blank to impart a channel-shaped cross sectional contour to the blank prior to rolling the latter to its final desired shape.

The foregoing, as well as other objects of the 30 present invention, will be made more apparent as this description proceeds, especially when considered in connection with the accompanying drawing, wherein:

Figure 1 is a fragmentary sectional view 35 through a rolling machine illustrating one of the steps of my improved method; and

Figures 2, 3, 4 and 5 are enlarged fragmentary 40 views showing other steps of the method about to be described.

Although various different types of apparatus 45 may be successfully employed in carrying out the several steps of my improved method about to be described, nevertheless, I have found that apparatus 50 of the character illustrated in my pending application, Serial No. 47,180, filed October 28, 1935, is particularly suitable for manufacturing vehicle wheel rims of the drop-center type in accordance with the present method. In 55 general, the apparatus comprises a male roll 10 secured to a rotatable spindle 11 and mounted for movement toward and away from a female roll 12. The cooperating peripheral or working surfaces of both rolls correspond in shape to the cross sectional contour of the rim shown in Fig-

ure 3, and the female roll 12 comprises two complementary sections 13 and 14. Each of these sections has the collar or ring 13' which extends axially over or overhangs the peripheral or working surface and which is engageable with the 5 adjacent edge of the blank and which is adapted to form a stop for positioning the blank. The roll section 13 is secured to a rotatable spindle 15, while the roll section 14 is secured to an aligned rotatable spindle 16, and both spindles 10 are mounted for movement toward and away from each other in the direction of their axes. Briefly, the arrangement is such as to permit the roll sections to be simultaneously moved in directions away from each other from the position of 15 the same shown in Figure 3, wherein they cooperate to form the roll 12 to a position wherein they are separated a sufficient distance to permit the rim blank A to be inserted therebetween.

It has previously been stated that the working 20 surfaces of the forming rolls 10 and 12 correspond in shape to the cross sectional contour of the rim shown in Figure 3. This particular contour is not exactly the same as the cross sectional contour of the completed rim shown in 25 Figure 5 and, accordingly, the apparatus embodies a second set of forming rolls 16' having the working faces thereof shaped to correspond exactly to the desired cross sectional contour of the completed rim. With the exception of the cross 30 sectional contour of the working faces of the roll 16', the latter are identical to the forming rolls previously described.

With the foregoing in mind, reference will now 35 be made to my improved method of forming vehicle wheel rims of the cross sectional contour shown in Figure 5. The first step in this method consists in introducing an annulus or rim blank A between the two complementary sections of the female roll when the latter are in their outermost 40 positions with respect to each other. The two aforesaid sections of the female roll are then caused to move toward each other to the position thereof shown in Figure 1, wherein the portions of the roll sections corresponding substantially 45 to the annular tire bead engaging seats of the rim telescope within opposite ends of the blank to support the latter. Upon continued movement of the roll sections towards each other the latter act in much the same manner as a die to curl the 50 opposite ends of the blank outwardly in the manner clearly shown in Figure 2, the blank being positioned relative to the roll sections by the collars or rings upon the roll sections engaging the opposite edges of the blank. During the aforesaid 55

operation of the roll sections, the latter may, or 5 may not, be rotated and, in the event they are not rotated, the same are revolved upon completion of the step illustrated by Figure 2. As the 10 complementary female roll sections continue to move toward each other, the rotatable male roll 10 is moved toward the axis of the roll sections so as to cooperate therewith in forming the blank to the cross sectional contour shown in Figure 3. 15 With the above arrangement, it will be seen that as the blank is rolled to the cross sectional contour shown in Figure 3, an axial pressure is simultaneously exerted upon opposite sides of the blank or upon the blank at opposite sides of its 20 axis by the female roll sections, and this is desirable in that it not only provides for reducing the number of rolling operations, but, at the same time, renders it possible to form a small diameter rim from relatively heavy gage stock. 25 Upon completion of the rolling operation noted in Figure 3, the complementary female roll sections are separated and the male roll is moved in a direction away from the sections so as to permit ejecting the rim blank from the machine 30 and conveying the same to a position between the female roll sections shown in Figure 4. The peripheral surface of the latter roll sections, when in engagement with each other, and the cooperating peripheral surface of the male roll 35 correspond in shape to the desired contour of the rim and cooperate with each other to perform the final rolling operation. After the rim blank has been positioned between the female rolls shown in Figure 4, the latter are moved toward each other into supporting engagement 40 with the rim blank and the male roll is moved toward the rim blank in timed relation to the movement of the female roll sections. Upon completion of the latter operation, the rolls are 45 in the position thereof shown in Figure 4, and upon continued movement of the female roll sections toward each other, the male roll section is simultaneously moved toward the axis of rotation of the female roll resulting in the application of a combined rolling and pressing action 50 upon the rim blank until the rolls assume the position thereof shown in Figure 5. During the aforesaid operation, the rim blank assumes its final cross sectional contour and is ejected from the apparatus after the male roll and female roll sections have been separated.

Thus, from the foregoing it will be observed that I have provided a method of forming vehicle wheel rims of the drop-center type composed of a relatively few steps and capable of being formed in a simple apparatus with the minimum amount of handling. It will also be apparent that due to the combined radial and axial pressures exerted upon the blank during the rolling operation, a relatively deep channeled rim of small diameter may be effectively fashioned. 5

Although in describing the present invention particular stress has been placed upon the use of my improved method for forming vehicle wheel rims of the drop-center type, nevertheless, it will be apparent that the several steps of this method 15 are equally applicable in forming an annulus to various different cross sectional contours and, therefore, this invention should not be considered as limited to forming rims of any specific cross 20 sectional contour.

What I claim as my invention is:

1. Those steps in the method of manufacturing annular members having a predetermined cross sectional contour which consist in introducing an annular blank between a pair of forming roll 25 sections cooperating in their innermost position to form a continuous contoured surface, flanging the opposite ends of the blank by relatively moving the roll sections toward each other into engagement with the ends of the blank, and rolling 30 the blank upon continued relative movement of the roll sections toward each other by exerting a radial rolling pressure on the blank while the latter is supported on the forming roll sections. 35

2. Those steps in the method of manufacturing annular members having a predetermined cross sectional contour which consist in introducing an annular blank between a pair of forming roll sections cooperating in their inner most position to form a continuous contoured surface, initially 40 flanging opposite ends of the blank by relatively moving the roll sections toward each other into engagement with said ends of the blank to exert a pressure on said ends in a direction axially of the blank, and exerting a radial pressure on the 45 blank in a direction toward the roll sections as relative movement of said roll sections toward each other is continued.
